UNITED STATES PATENT OFFICE.

ISAAC LEVY, OF BROOKLYN, NEW YORK.

DESIGN FOR A LIGHTING-FIXTURE BACKPLATE OR ANALOGOUS ARTICLE.

Application filed August 10, 1927. Serial No. 23,046. Term of patent 3½ years.

To all whom it may concern:

Be it known that I, ISAAC LEVY, a citizen of the United States, and a resident of Brooklyn, county of Kings, and State of New York, have invented a new, original, and ornamental Design for a Lighting-Fixture Backplate or Analogous Article, of which the following is a specification, reference being had to the accompanying drawing, forming a part hereof.

The figure in the drawings shows a perspective view of the lighting fixture back plate.

I claim:

The ornamental design for a lighting fixture backplate or analogous article substantially as shown.

ISAAC LEVY.
